UNITED STATES PATENT OFFICE.

WILLIAM HOOD, OF SAN FRANCISCO, CALIFORNIA.

FEATHER-WASHING MACHINE.

Application filed September 2, 1924. Serial No. 735,337.

To all whom it may concern:

Be it known that I, WILLIAM HOOD, a citizen of the United States, residing in the city and county of San Francisco and State of California, have invented a new and useful Improvement in a Feather-Washing Machine, of which the following is a specification.

My invention relates to improvements in feather washing machines and the like wherein feathers to be cleaned are moved by a stirring element through a cylindrical screen rotating in a detergent solution, the feathers being introduced at one end of the screen and removed at the other end of the screen continuously while the screen and stirring element are in operation.

The primary object of my invention is to provide an improved machine for washing feathers and the like.

Another object is to provide an improved machine adapted to permit the introduction and removal of feathers while the machine is in operation.

A further object is to provide a machine of the character described which will quickly and effectively clean the feathers and separate all dirt and refuse therefrom.

Another object is to provide a device which will facilitate the cleaning and drying of feathers in large quantities.

A still further object is to provide a device wherein a stirring element is arranged to agitate feathers to be cleaned in a detergent solution and to create a current in the solution whereby the feathers are moved forwardly through the machine and dirt and refuse separated from the feathers.

I accomplish these and other objects by means of the device disclosed in the drawings forming a part of the present specification wherein like characters of reference are used to designate similar parts throughout said specification and drawings and in which,

Fig. 1 is a longitudinal vertical section of my improved feather washing machine.

Figs. 2 and 3 are left and right end elevations respectively of the machine as shown in Fig. 1.

Fig. 4 is a transverse vertical section taken upon the line 4—4 of Fig. 1 in the direction indicated.

Fig. 5 is a broken side elevation of one end of the machine.

Referring to the drawings the numeral 1

is used to designate in general a tank adapted to receive a quantity of a detergent solution adapted for the cleaning of feathers and the like. A pair of parallel shafts 2 extend longitudinally through the tank, said shafts being spaced horizontally.

A cylindrical screen 3 is mounted for rotation within the tank 1, said screen being open at both ends and being provided with annular gear portions 4 and 6 mounted adjacent the ends. The gear portions 4 and 6 mesh with gears 7 secured in pairs in corresponding positions upon the shafts 2 the weight of the screen being supported upon the pairs of gears so that rotation of the shafts 2 will cause a rotation of the cylindrical screen 3 within the tank. One end of the screen is arranged in proximate relation with an end of the tank 1. The opposite end of the screen is provided with a solid sleeve portion 8 the end of which is spaced away from the adjacent end of the tank.

A pan 9 is secured upon the end of the tank 1, said pan extending across the end of the tank and having an arcuate bottom underlying the end of the sleeve portion 8 of the screen in slightly spaced relation thereto to form a narrow passage 10 between said sleeve and the pan for a purpose hereinafter more fully explained.

A stirring element is mounted for rotation within the cylindrical screen 3, said element consisting of a shaft 11 centrally disposed with respect to the screen and provided with a plurality of stirrers 12 secured in longitudinally and angularly spaced relation defining a spiral along the shaft. The stirrers 12 are preferably formed from round rods threaded into the shaft at one end and having the other end flattened and slightly twisted with respect to the axis of the rod in the shape of a propeller blade. The tank 1 is filled with solution to a point slightly below the shaft 11 so that the stirrers will dip into the surface of the solution when the shaft 11 is rotated as hereinafter described and thereby create a forward current in the upper portion of the solution for a purpose hereinafter more fully explained.

The shafts 2 are driven simultaneously in the same direction and at the same speed by means of a chain 13 mounted over sprockets 14 secured upon the ends of the shafts, power being applied to one of said shafts 2 through a pulley 16 secured thereon. The shaft 11 is driven by means of a chain 17 mounted

over a small sprocket 18 secured upon the end of the shaft 11 and a large sprocket 19 secured upon the power shaft 2 whereby the stirring element is rotated in the same direction as the shafts 2 but at a greater speed. The screen 3, being driven by the gears 7, is caused to rotate in the direction opposite to the direction of rotation of the stirring element so that when the machine is in operation the screen and the stirring element will be rotated simultaneously in opposite directions and at different speeds.

A conduit 21 is connected into the end of the tank 1 to communicate with the interior of screen 3 at the end remote from the sleeve 8 and pan 9, feathers being introduced into the screen through said conduit by means of a suitable blower, not shown.

A conveyer 22 is mounted upon the opposite end of the tank 1, said conveyer consisting of a chain passing over suitable sprockets 23 mounted upon shafts 24 and 25, one of which is positioned below the level of the solution within the tank and the other positioned above the top of the tank. A plurality of dippers 26 provided with screen bottoms 27 are secured upon the chain and arranged to be moved by said chain along a path immediately adjacent the pan 9 and thence upwardly along the inclined path to a point above the top of the tank. The conveyer 22 is driven by means of gears 28 and 29 mounted upon the shafts 11 and 24 respectively.

A pair of proximate rollers 31 are mounted upon suitable supports secured upon the upper edge of the tank 1, said rollers being geared together by means of gears 32 and actuated by a chain 33 driven by a sprocket 34 mounted upon the end of the shaft 11 and operating the rollers through suitable reduction gears 36 and 37. A chute 38 is mounted between the upper portion of the conveyer and the rollers to receive feathers from the conveyer and direct said feathers between the rollers.

In operation, power is applied from any suitable source, not shown, through the pulley 16 to rotate the screen and stirring element and to operate the conveyer 22 and the rollers 31 as above described, the tank being filled with detergent solution to a point slightly below the level of the shaft 11. Feathers are now blown into the rotating screen 3 through the conduit 21.

The rotation of the stirring element causes the stirrers to agitate the feathers in the solution. At the same time, the propeller shape of the stirrers causes a current to be set up in the upper portion of the solution which will carry the feathers forwardly through the screen. The movement of the feathers through the solution causes the feathers to be thoroughly cleaned and any dirt or refuse present to be separated from

the feathers, such dirt and refuse passing through the interstices of the screen and settling to the bottom of the tank as the feathers are moved forwardly through the tank.

The feathers are carried by the action of the stirrers and the current caused thereby into the space above the pan 9. As the conveyer moves along its path above the pan the dippers 26 are moved into the solution and upon the upward movement scoop up feathers from the solution, the solution being drained off through the screen bottoms of the dippers and the feathers elevated to a point above the top of the tank. As the dippers are moved over the upper sprocket 23 the feathers drop off onto the chute 38 and are directed thereby between the rotating rollers 31 whereby any solution which has not drained off from the feathers is squeezed out.

The current caused by the stirrers causes a return flow of the solution through the passage 10 between the pan 9 and the sleeve portion 8 of the screen thereby flushing any dirt or refuse which may be carried forward with the feathers into the pan back into the tank 1, such dirt and refuse settling in the forward end of the tank due to an eddy caused by the circulation of the solution through the tank and around the pan 9.

From the above explanation it will be seen that feathers may be introduced continuously into one end of the rotating screen 3 and removed by means of the conveyer 22 from the opposite end of the screen, in this manner permitting feathers to be washed and cleaned by a substantially continuous process whereby large quantities of feathers may be efficiently cleaned.

Having thus described my invention what I claim as new and desire to secure by Letters Patent is,

1. A feather washing machine comprising a tank adapted to receive a detergent solution; a cylindrical screen mounted within the tank; means for introducing feathers to be cleaned into one end of the screen; a stirring element mounted within the screen and provided with a plurality of propeller shaped stirrers adapted to agitate the feathers within the solution and to create a current to carry the feathers forwardly through the screen; means for rotating the screen and the stirring element simultaneously in opposite directions; a pan in association with the other end of the screen to receive feathers from said screen; and a conveyer mounted adjacent said end of the screen and operating within said pan to remove the feathers from the solution.

2. A feather washing machine comprising a tank adapted to receive a detergent solution; a cylindrical screen mounted for rotation within the tank; means for introducing feathers to be cleaned into one end of

the screen; a stirring element mounted for rotation within the screen, said element being provided with a plurality of propeller shaped stirrers adapted to agitate the feathers within the solution and to create a current in said solution to carry the feathers forwardly through the screen; a pan mounted in association with the other end of the screen to receive the feathers from the screen; and a conveyer mounted adjacent said end of the screen and provided with a plurality of screen bottomed dippers adapted to scoop up feathers from the pan and remove said feathers from the tank.

3. A feather washing machine comprising a tank adapted to receive a detergent solution; a cylindrical screen mounted for rotation within the tank; means for introducing feathers into one end of the screen; a stirring element mounted for rotation within the screen, said stirring element being provided with a plurality of propeller shaped stirrers adapted to agitate the feathers within the solution and to create a current in said solution to carry the feathers forwardly through the screen; a pan mounted in association with the other end of the screen to receive feathers from said screen, said pan underlying the end of the screen and being slightly spaced below the end of the screen to form a passage between said pan and the end of the screen through which dirt from the feathers may be carried by the current set up by the stirrers; and a conveyer mounted adjacent the end of the screen and provided with a plurality of screen bottomed dippers adapted to scoop up feathers from the pan and remove said feathers from the reservoir.

4. A feather washing machine comprising a tank adapted to receive a detergent solution; a pair of parallel shafts mounted within the tank and extending longitudinally therethrough; gears mounted in corresponding positions upon said shafts; a cylindrical screen provided with annular gear portions adjacent the ends, said gear portions meshing with the gears carried by the propeller shafts and supporting the weight of the cylinder whereby a rotation of the shafts operates to rotate the cylinder within the tank; means for introducing feathers to be cleaned into one end of the cylindrical screen; a stirring element mounted within the screen and consisting of a shaft extending longitudinally through the tank and provided

with a plurality of propeller shaped stirrers adapted to agitate the feathers in the solution and to create a current in said solution to carry the feathers forwardly through the screen; means connecting one of the screen supporting shafts with the stirring element shaft for rotating the stirring element in a direction opposite to the rotation of the screen and at a greater speed; and a conveyer mounted adjacent the opposite end of the screen and provided with a plurality of screen bottomed dippers for removing the feathers from the tank.

5. A feather washing machine comprising a tank adapted to receive a detergent solution; a pair of parallel shafts mounted within the tank and extending longitudinally therethrough; gears mounted in corresponding positions upon said shafts; a cylindrical screen open at both ends, one end being positioned against one end of the reservoir and the other end provided with a solid sleeve having the outer end spaced from the adjacent end of the tank, said screen being provided with annular gear portions meshing with the gears upon the parallel shafts and supporting the weight of the cylinders whereby a rotation of said shafts operates to rotate the screen; a pan mounted within the reservoir adjacent to and underlying the sleeve upon the cylindrical screen, said sleeve being slightly spaced below the sleeve to form a narrow passage therebetween; means for introducing feathers into the opposite end of the screen; a stirring element mounted within the cylindrical screen and consisting of a centrally disposed shaft provided with a plurality of propeller shaped stirrers adapted to agitate the feathers within the solution and to create a current in said solution to carry the feathers forwardly through the screen dirt and refuse being carried from the pan through the passage between said pan and the sleeve; means connecting one of the screen supporting shafts with the stirring element shaft for rotating the stirring element in a direction opposite to the direction of rotation of the screen and at a greater speed; and a conveyer mounted adjacent the end of the sleeve and provided with a plurality of dippers adapted to scoop feathers from above the pan and remove said feathers from the tank.

In witness whereof I hereunto set my signature.

WILLIAM HOOD.
